UNITED STATES PATENT OFFICE.

JOSEPH P. HOLSING, OF HIGH SPLINT, KENTUCKY.

RAIL BOND.

Application filed November 14, 1923. Serial No. 674,674.

To all whom it may concern:

Be it known that I, JOSEPH P. HOLSING, citizen of the United States, residing at High Splint, in the county of Harlan and 5 State of Kentucky, have invented certain new and useful Improvements in Rail Bonds, of which the following is a specification.

This invention relates to electrical connectors and has particular reference to an improved form of rail bond by means of which rail sections may be electrically connected at their joints so that the rails may 10 act as conductors of electricity.

15 The primary object of the invention is to provide a rail bond of simple and durable construction, and one that will be efficient in operation.

Another object of the invention is to provide a rail bond which may be expeditiously 20 applied to the rails and wherein the bonding or connecting wire is positioned so as to render damage of the same unlikely, due to the wheels of a de-railed car engaging the 25 same.

With the above general objects in view and others that will become apparent as the 30 nature of the invention is better understood, the same consists in the novel form, combination, and arrangement of parts herein- 35 after more fully described, shown in the accompanying drawing, and claimed.

In the drawing, wherein like reference 40 characters designate corresponding parts throughout the several views:

Figure 1 is a side elevational view, partly in section, of a rail bond constructed in accordance with the present invention and operatively disposed upon the adjacent ends 45 of abutting rail sections.

Figure 2 is a view of Figure 1, partly in horizontal section, and partly in top plan, and

45 Figure 3 is a view of the device shown in Figure 1, partly in transverse section, and partly in end elevation.

Referring more in detail to the drawing, 5 and 6 indicate the abutting rail sections that are to be bonded. The present bonding 50 device comprises a pair of clips or clamps 7 or 8 formed and adapted to pass transversely of and under the base of the rails and then inwardly on the upper surface of the base thereof, so that the free ends of 55 each clamp terminate at opposite sides of

the rail web at the point of juncture between said web and the main flanges of the rail. It is to be understood that one clamp or clip is disposed upon the adjacent end of each rail section as shown in Figures 1 and 2, and in 60 order to permit ready application of said clamps or clips, they are purposely formed of a pair of hingedly connected sections, the pivot of which is indicated at 9, and which allows the smaller section to swing in a vertical plane upon a horizontal axis that extends parallel with the rail.

The inner end of the other clamp section of each clamp is provided with a sleeve or socket 10 that is open at its ends and disposed longitudinally of the rail at the point of juncture between one of the base flanges of the rail and the web thereof as shown clearly in Figure 3. In order to maintain the clamps upon the rails, the smaller sections of said clamps are provided with set screws 11 in the free ends thereof adapted to be threaded into suitable sockets provided in the upper surface of the adjacent base flange of the rail as shown in Figure 3. 75 In this manner, creeping of the clamps is prevented and a good electrical connection made between the clamps and the rail.

The socket 10 of the shoe clamps are provided with suitable set screws 12 by means 80 of which the ends of the connecting or bonding wire 13 may be effectively secured therein so as to be capable of being easily removed if desired for renewal or other purposes, and when the wire is arranged with 85 its ends within the sockets of the two clamps, said wire is positioned beneath the adjacent side of the ball of the rail so as to be fully protected.

From the above description, it is believed 90 that the construction and operation, as well as the advantages of the present invention will be readily understood and appreciated by those skilled in the art.

What I claim as new is:

1. A rail bond comprising a pair of clamps adapted to embrace the bases of abutting rail sections with their ends terminating at opposite sides of the webs of the rail sections at the junctures of the rail webs with the base flanges, aligned sockets rigid upon adjacent ends of said clamps, a bonding wire having its ends disposed within said sockets, means for securing the ends of said bonding wires in said socket, said 110

- clamps comprising hingedly connected sections, one clamp section of each clamp having a transverse set screw through an end thereof adapted to be threaded in a socket 5 in the upper surface of the adjacent base flange of the rail for maintaining the clamp upon the base of the rail and for preventing creeping of the clamp longitudinally of the rail.
- 10 2. A rail bond wire clamp shaped to surround the base flange of a rail, such clamp being composed of hingedly connected sec-

tions, the inner ends of which are adapted to be disposed in close proximity to the web of the rail, one of said ends being provided with a transversely disposed open ended sleeve forming a socket for reception of the wire, set screws carried by said socket, and additional set screws carried by the other section of the clamp for connecting the 15 clamp to the rail.

In testimony whereof I affix my signature.

JOSEPH P. HOLZING.
